UNITED STATES PATENT OFFICE.

EDWARD D. PUTT, OF AKRON, OHIO, ASSIGNOR TO THE FIRESTONE TIRE AND RUBBER COMPANY, OF AKRON, OHIO, A CORPORATION OF OHIO.

TIRE-STRIPPING MACHINE.

Application filed May 12, 1923. Serial No. 560,884.

To all whom it may concern:

Be it known that I, EDWARD D. PUTT, a citizen of the United States, residing at Akron, in the county of Summit, State of Ohio, have invented certain new and useful Improvements in Tire-Stripping Machines, of which the following is a specification.

My invention relates to improvements in tire stripping machines for use in removing 10 pneumatic tire casings from the cores upon which they have been either built or vulcanized.

Broadly stated, the primary purpose of the invention is to provide an improved 15 form of apparatus adapted for operation to remove a casing from a core while the core is being held in suspended position as, for instance, by means of the mechanism disclosed in the patent to William C. Stevens, 20 No. 1,211,256, dated January 2, 1917.

Specifically, the invention is directed toward providing improvements in the devices of the aforesaid patent that engage the casing and the core to effect the stripping 25 operation, one of the particular results sought, in the present instance, being to so direct the action of these devices that they are always positioned at the proper angle relative to the core to minimize the strain 30 upon them and upon their mountings and their action in separating the casing from the core is facilitated.

Other objects and advantages will presently appear and the nature of the invention will be more fully understood when the following description is read in conjunction with the drawings accompanying and forming a part of this specification.

In the drawings:

Figure 1 is a vertical transverse section 40 illustrating the application of my invention, upon a preferred type of core stripping and supporting mechanism;

Figure 2 is a front elevational view of the 45 mechanism shown in Figure 1;

Figure 3 is a transverse sectional view, 50 illustrating on an enlarged scale, the starting position of my improved stripping elements relative to a core and casing;

Figure 4 is a view similar to Figure 3 55 illustrating an intermediate position of my improved stripping elements relative to a core and casing;

Figure 5 is a front elevational view of so much of the devices as are shown in Figures 55 3 and 4;

Figure 6 is a detail perspective view of one of the elements comprising my invention;

Figure 7 is a perspective view of another of the elements comprising my invention; 60 and

Figure 8 is a perspective view of still another element of the invention.

In the type of machine with which my invention has been illustrated, a core 1 is 65 elevated and suspended in a vertical position in front of a pair of normally vertical guide arms 2 that are pivotally mounted for movement to swing their outer ends in opposite directions circumferentially of the core 1. 70 Each arm 2 is equipped with a slide 3 which is adapted to be reciprocated relative to its arm to move it vertically and then swing by its arm circumferentially of the core.

The mechanism for elevating the core, 75 moving the arms 2, and reciprocating the slides 3 forms, per se, no part of the present invention and will, therefore, not be described in detail herein. Briefly described, it 80 comprises two parallel cross shafts 4 and 5, the latter of which is continuously driven from a motor 6 by a gear train comprising gears 7, 8, 9 and 10. A pair of one revolution clutches 11 and 12 are mounted upon the shaft 5 in relatively spaced relation 85 which are adapted for operation to clutch and release the shaft by means of a control mechanism designated generally by the numeral 13. One of the clutches, preferably 11, has fixed thereto a gear pinion 14 which 90 meshes with a pinion 15 fixed upon a sleeve 16. The sleeve 16 is rotatably mounted upon the shaft 4 and carries a cam 17. Cam 17 engages a roller 18' upon the rear end of a bell crank lever 18, that is pivotally mounted 95 for movement in a vertical plane, and serves to rock the lever 18 upon its pivot 19. The core 1 is positioned upon the forward end of this bell crank lever 18 and is raised thereby to a proper position in front of the 100 arms 2 previously mentioned. A second pivotally mounted lever 20 serves to reciprocate the slides 3 in the arms 2. This lever is pivoted as at 21 intermediate its length and at its rear end is provided with 105 a roller 22 that is likewise engaged by the

cam 17. At its forward end the lever 20 actuates a cross head 22 which is connected by means of pitmen 23 to each of said slides 3. The relative arrangement of the levers 18 and 20 and the cam 17 are such that the core is first elevated and the slides 3 are then reciprocated from their lowermost position upwardly past the upper portion of the core 1.

10 At this point in the operation of the machine the rotation of the cam is stopped until the arms 2 and the slides 3 thereon are swung circumferentially of the core. This latter operation is effected in the following manner: Clutch 12 carries a gear pinion 24 in mesh with a gear pinion 25 that, in turn, is fixed upon the shaft 5. Shaft 5 at each end thereof is equipped with a beveled gear 26 which mesh respectively with corresponding gears 27. Gears 27 are fixed respectively upon short shafts 28 which are journaled for rotation about individual axis at right angles to the axis of rotation of shaft 5. As shown in Figure 2, the arrangement of shafts 28 is such that the arms 2 are between them and their axis are below the horizontal diameter of the core 1. A crank arm 29 and a link 30 serves to connect each shaft 28 to one of the arms 2 in such manner that when the shafts 28 are rotated the arms are swung in opposite directions about their respective pivots 31 from a vertical position to substantially a horizontal one.

15 The slides 3 are equipped with my improved stripping devices which will now be described in detail.

20 Each slide 3 is provided at its upper end with an outstanding lug 32, upon which is mounted a balanced two part roller mounting that is suspended for oscillating movement, as a unit, relative to its slide 3 and the core 1. Each mounting preferably comprises a depending arm 33, that is bifurcated at its upper end, as at 34, and pivotally mounted upon a pintle 35 which passes through its bifurcated portion 34 and its associated lug 32. The lower end of each arm 33 is also preferably bifurcated as at 35 and extends forwardly of the arm at a right angle thereto to provide an offset support for an arm 40, presently described. Between its bifurcated portions 34 and 35, each arm 33 is chambered, as at 37, to receive a headed pin 38 that is normally pressed toward the core by a compression spring 39. Upon the portion 35 of each arm 33 a normally upwardly pivoted arm 40 is mounted for swinging movement thereon, in a vertical plane, and toward and away from the core 1.

25 A suitable coil spring 41 is arranged about the pivot, designated 42, of the arm 40, whereby said arm is held in yielding engagement with the spring pressed pin 38 of its arm 33. Upon the upper end of each arm 40, a flanged roller 43 is mounted to rotate freely about a spindle 44 that projects forwardly of its arm toward the core 1. These rollers each include a front flange 45 and a rear flange 46 for a purpose presently apparent. Preferably the spindle 44 of each arm 40 is inclined downwardly and laterally and the relative angle of inclination of the spindles is such that they converge at their free ends as best shown in Figure 2 of the drawings. The rollers 43 are designed to pass transversely over the face of the core 1 on the up stroke of the reciprocable slides 3, the front flange 45 of each roller prying the casing loose from the core. By virtue of the relative inclination of the spindles previously described, the forward faces of each flange 45 are presented against the core surface at such a tangent thereto that this prying or separating action is facilitated. At this point it should be noted that the relative arrangement and construction of the springs 39 and 41 are such that the arms 33 and 34 are held in yielding balanced relation to permit the rollers 43 to wipe over the casing and core on the down stroke of the slides 3.

30 Upon each guide arm 2 a cam plate 47 is mounted as best shown in Figures 2 and 5 of the drawings. Each cam plate 47 has an inclined end portion 48 and a straight portion 49. Upon the lower end of each arm 33 a roller 50 is mounted in position to engage one of the cam plates 47. The arrangement of the plates 47 is such, that as the slides are lowered, and the rollers 43 wipe past the core, each arm 33 has its lower end swung outwardly toward the core, so that at the beginning of the up stroke of the slides 3, the rollers 43 are presented against the core in substantially the position shown in Figure 3 of the drawings. That is to say, in a position for the forward flanges 45 of the rollers to take under the bead of a casing and between it and the core, and the direction of thrust of the roller is at an obtuse angle to the surface of the core. The obtuse angle is maintained until the rollers have passed the horizontal diameter of the core annulus and a minimum strain is thus imposed upon the mounting and its pivotal connections. As the rollers 43 reach substantially the horizontal diameter of the core annulus, the rollers 50 pass on to the inclined portions of the cams and the lower end of arms 33 gradually move away from the core. Arms 40 are now forced away from the arms 33 by the action of the weight and resistance of the casing on the rollers 43 and the rollers 50 are adjusted to maintain their angular position relative to the transverse curvature of the core as the arms 33 and 40 swing about the pivot pintle 35 toward the slides 3. The cam plates 47 are so disposed and constructed that this latter adjustment of the rollers 43 continues until said rollers round

the top of the core. At this point in their movement, the rollers are moved circumferentially of the core by the mechanism previously described.

5. The coil spring 41 and the pin 38 serve to keep the roller in proper position to engage the tire casing.

Although I have described my invention in detail and necessarily utilized certain specific language herein, it is to be understood that the present disclosure is illustrative and is not to be construed as limiting the scope or spirit of the invention unless such limitations are expressly indicated in the claims 15 appended hereto.

What I claim is:

1. Apparatus for stripping tire casings from cores comprising in combination, means for supporting a core and casing thereon, and means for stripping the casing from the core, said stripping means including a reciprocable slide, a roller, and a shiftable mounting for the roller mounted on said slide.

2. Apparatus for stripping tire casings from cores comprising in combination, means for supporting a core and casing thereon, and reciprocable means for stripping the casing from the core embodying a roller adapted to transverse the core, a movable mounting for the roller adapted to press the roller against the core, and means to maintain the mounting in one position at the beginning of the stripping 35 action and permit it to move during the stripping movement.

3. Apparatus for stripping tire casings from cores comprising in combination, means for supporting a core and casing 40 thereon, means for stripping the casing from the core comprising a roller and a pivoted mounting therefor and means to cause the mounting to recede from the core at a predetermined point in the stripping 45 operation.

4. Apparatus for stripping tire casings from annular cores comprising in combination, means for supporting the core and casing thereon, a roller, means adapted to move 50 the roller transversely of the core annulus, a mounting constructed to support the roller upon said means in engagement with the core, and cam means for changing the position of the mounting as the roller is moved transversely of the core.

5. Apparatus for stripping tire casings from annular cores comprising in combination, means for supporting a core and casing 55 thereon, a reciprocable slide adapted to move transversely of the core, an oscillatable mounting upon the slide, a roller upon the mounting adapted to transverse the core annulus during reciprocation of the slide, and cam means for oscillating the 65 mounting.

6. Apparatus for stripping tire casings from annular cores comprising in combination, means for supporting a core and casing thereon, a vertically reciprocable slide adapted to move transversely of the core 70 annulus, a roller, and a mounting adapted to support the roller upon the slide said mounting embodying relatively movable arms normally held in yielding angular position with respect to each other. 75

7. Apparatus for stripping tire casings from annular cores comprising in combination, means for supporting a core and casing thereon, a vertically reciprocable slide adapted to move transversely of the core 80 annulus, a roller, and a mounting for yieldably supporting the roller on the slide embodying relatively movable arms adapted for swinging movement as a unit about a common axis. 85

8. Apparatus for stripping tire casings from annular cores comprising in combination, means for supporting a core and casing thereon, a vertically reciprocable slide adapted to move transversely of the core 90 annulus, a roller, an adjustable mounting adapted to support the roller upon the slide said mounting embodying relatively movable arms normally held in yielding angular position with respect to each other, and cam 95 means for adjusting the mounting.

9. Apparatus for stripping tire casings from annular cores comprising in combination, means for supporting a core and casing thereon, a vertically reciprocable slide 100 adapted to move transversely of the core annulus, a roller, a mounting for yieldably supporting the roller on the slide embodying relatively movable arms adapted for swinging movement as a unit about a common axis, and means for swinging the mounting during reciprocation of the slide. 105

10. Apparatus for stripping tire casings from annular cores comprising in combination, means for supporting a core and casing thereon, a vertically reciprocable slide 110 adapted to move transversely of the core annulus, a depending arm pivotally mounted upon the slide for swinging movement thereon, an upstanding arm on said first arm yieldably held in angular relation with respect thereto, and a roller upon said last arm adapted to engage the side of the core on the up stroke of the slide. 115

11. Apparatus for stripping tire casings 120 from annular cores comprising in combination, means for supporting a core, a vertically reciprocable slide adapted to move transversely of the core annulus, a depending arm pivotally mounted for swinging movement on the slide, a roller upon the arm, a cam plate adapted to engage the roller to move the arm away from the slide, and a flanged roller yieldably mounted upon the arm for engagement with the core. 125 130

12. Apparatus for stripping tire casings from annular cores comprising in combination, means for supporting a core and casing thereon, a vertically reciprocable slide adapted to move transversely of the core annulus, a depending arm pivotally mounted upon the slide for swinging movement relative thereto, a roller upon the arm, a cam plate adapted to engage the roller to move the arm away from the slide, and a flanged roller yieldably mounted upon the arm for engagement with the core and for movement in an arcuate path.

EDWARD D. PUTT.
